UNITED STATES PATENT OFFICE.

PETER H. FULLER, OF DOBBS FERRY, NEW YORK.

DESIGN FOR A LOUD SPEAKER OR THE LIKE.

Application filed March 6, 1928. Serial No. 25,718. Term of patent 7 years.

To all whom it may concern:

Be it known that I, PETER H. FULLER, a citizen of the United States, and a resident of Dobbs Ferry, in the county of Westchester and State of New York, have invented the new, original, and ornamental Design for Loud Speaker or the like, of which the following is a specification.

In the accompanying drawings—

loud speaker or the like, showing my new design;

Figure 2 is a top plan view of the same.

I claim:

The ornamental design for a loud speaker or the like, as shown.

Signed at New York, in the county of New York and State of New York this 5th day of March A. D. 1928.

PETER H. FULLER.
